UNITED STATES PATENT OFFICE.

ISABEL IRENE ELTERICH, OF FREEPORT, NEW YORK.

SHIELD FOR LADIES' DRAWERS

No. 872,172.

Specification of Letters Patent.

Patented Nov. 26, 1907.

Application filed March 9, 1907. Serial No. 361,586.

To all whom it may concern:

Be it known that I, ISABEL IRENE ELTERICH, a citizen of the United States, residing in Freeport, in the county of Nassau, State 5 of New York, have invented certain new and useful Improvements in Shields for Ladies' Drawers, of which the following is a specification.

This invention relates to an improved 10 shield for ladies' drawers, which shield is intended to be basted on to the edge of the crotch-part of ladies' open drawers so as to be easily removed when soiled for washing.

The object of the invention is to protect 15 the drawers at the parts most exposed to soiling and wear, and permit thereby the longer use of the same and to keep them in a cleaner condition for wear.

For this purpose the invention consists of a 20 shield for ladies' drawers comprising a main-piece of fabric composed of two approximately triangular portions stitched together, and an overlap extending along the upper curved edge of the main-piece, as will be fully 25 described hereinafter and finally pointed out in the claims.

In the accompanying drawings, Figure 1 represents a front-elevation of a pair of ladies' 30 drawers showing my improved shields applied to the same, Fig. 2 is a rear-elevation of the drawers, Fig. 3 is a detail top-view of a right-hand shield, and Fig. 4 is a top-view of the parts from which my improved shield is made.

Similar reference characters indicate corresponding parts throughout the several 35 figures.

Referring to the drawings, D represents a 40 pair of ladies' drawers and A, A¹, a pair of shields, one being a left-hand and the other a right-hand shield, which shields are applied to the crotch part of the drawers, as shown in Fig. 1. The shields are so formed as to fit 45 and cover the crotch-edges of the drawers and cover that portion of the drawers at the crotch that is most exposed to soiling and wear.

The shields are made of ribbed, stocking- 50 ette, knit, absorbent, or other suitable fabric, and are formed each of three parts, a main-piece which is composed of two approximately triangular pieces a, b, that are stitched together at d, and an overlap-portion c which is made in one piece and

stitched to the curved upper edge of the 55 main-piece a, b, as shown clearly in Figs. 1 and 3. The entire outer edge of the shield is finished off by overseam or buttonhole stitches e so as to prevent raveling and to permit the easy basting on of the shield along 60 its edges and along the over-lap onto the drawers.

For applying a pair of shields as shown in Fig. 3 to drawers as shown in Fig. 1, place seam d of the right-hand shield on right side 65 of Fig. 1, place the portion a of shield on the outside of Fig. 1, place the portion b of shield on the outside of Fig. 1, back of seam, place overlap c around the entire crotch-part, the overlap being turned over on the 70 inside of the drawers, thus entirely covering the crotch-edge of drawers, the parts a and b being on the outside of the drawers. The entire edge e is then basted or sewed to the drawers as the case may require, perfectly 75 fitting the same and shielding that portion of the drawers most exposed to soil and wear. The left-hand shield is then fitted to the left-hand drawer-leg in the same manner as described for the right-hand leg. When the 80 shields are soiled they are removed for washing, another clean pair being applied to the drawers in their place.

Having thus described my invention, I claim as new and desire to secure by Letters 85 Patent:

1. A shield for ladies' drawers, consisting of a main-piece of fabric composed of two approximately triangular portions stitched together, and an overlap-portion stitched to 90 the upper curved edge of the main-piece.

2. The combination, with a pair of drawers having an open crotch, of shields applied to the edges of the crotch and each comprising a main-piece of fabric composed of two approximately triangular portions stitched together and extending outwardly over the crotch, and an overlapping portion stitched to the edge of the main-portion and extending inwardly over the edges of the crotch. 95 100

In testimony, that I claim the foregoing as my invention, I have signed my name in presence of two subscribing witnesses.

ISABEL IRENE ELTERICH.

Witnesses:
